UNITED STATES PATENT OFFICE

2,531,929

FISHING REEL

Walter Willman, St. Petersburg, Fla., assignor to
 James Heddon's Sons, Dowagiac, Mich., a corporation of Michigan

Application March 5, 1947, Serial No. 732,617

7 Claims. (Cl. 242—84.1)

1

This invention is concerned with a fishing reel of the type which utilizes at one end a head plate in the form of an annular ring providing a mounting for a cap plate assembly which includes a closure plate adapted to fit into and cover the opening in the head plate. By some such means protection is furnished to the gear train and other operating parts which may be carried by the cap plate assembly which, as a unit, is removably secured to the head plate. The particular features of invention with which I am here concerned relate primarily to the means whereby the cap plate and its assembly of parts may be securely locked to the head plate, yet be readily unlocked therefrom when occasion may require, to permit removal of the cap plate assembly from the reel, thereby to facilitate adjustment, repair, or replacement of any of the operating parts, as required.

Certain suggestive embodiments of this invention are illustrated in the accompanying drawings wherein:

Fig. 1 is a view in perspective of the reel in its entirety, showing assembled therewith the cap plate whose assembly of parts is enclosed within the space between itself and the head plate to which it is secured;

Fig. 2 is a transverse section through the reel, taken on line 2—2 of Fig. 1;

Fig. 3 is a view in perspective showing the closure plate supported from the inner side of the cap plate;

Fig. 4 is a fragmentary detail in section, taken in the same plane as Fig. 2, showing the closure plate of the cap plate assembly spaced slightly from the head plate of the reel;

Fig. 5 is a fragmentary detail in section, taken on line 5—5 of Fig. 6;

Fig. 6 is a view in end elevation looking toward the cap plate, a portion whereof is broken away to exhibit the closure plate to the inside thereof;

Fig. 7 is a view in perspective of one of the locking disks that may be employed to secure the cap plate assembly to the reel;

Fig. 8 is a transverse section through the locking disk.

Fig. 9 which is a transverse section, taken on line 9—9 of Fig. 10, shows a locking means of modified construction;

Fig. 10 is a view in section, taken on line 10—10 of Fig. 9;

Fig. 11 is a detail in perspective of the locking means shown in Figs. 9 and 10;

Fig. 12 which is a view in end elevation looking

2

toward the cap plate shows a further modified construction of locking means;

Fig. 13 is a detail in section, taken on line 13—13 of Fig. 12;

Fig. 14 is a view in perspective of the locking means per se shown in Figs 12 and 13;

Fig. 15 which is a view similar to Fig. 9 shows a locking means of still different construction;

Fig. 16 is a view in section taken on line 16—16 of Fig. 15; and

Fig. 17 is a view in perspective of the locking means shown in Figs. 15 and 16.

The principal operating units of the present reel may be of any conventional type, either with or without provision for level winding. It will be understood, therefore, that the present invention is not directed to specific details in the arrangement of the gears, or such accessory features as a click, drag, or level winding device.

For purposes of illustration, I have chosen a relatively simple type of reel comprising the usual clip plate 20 which may be carried by a pair of lower pillars 21 which, in conjunction with a side pillar 22 (one or more) and a top pillar 23, serves to interconnect a tail plate 24 with the head plate 25 which is here shown to be in the form of an annular ring. The pillars at their head ends are inwardly shouldered to provide reduced necks 27 which are closely fitted within holes formed through the head plate 25, the ends of the necks terminating substantially flush with the outer face of the head plate.

As shown in Fig. 5, there is extended axially into each pillar neck, from its outer end, a threaded socket wherein may engage a threaded stem 28 which extends axially from the inner end of a spacer post 29 of increased diameter, this post being shown as formed with a transverse hole 30 through which may be entered a small implement to apply a rotary force thereto.

When the post is turned to advance its stem within the pillar socket, the inner end of the post will be brought home against the outer face of the head plate 25 whereby to become fixed rigidly with respect thereto. The outer end of each spacer post is shouldered inwardly to provide a reduced neck 31 which may be closely fitted within a registering hole in a cap plate 32. The end of this neck which terminates substantially

flush with the outer face of the cap plate, is adapted to withdraw freely from the hole 32 when the cap plate is taken off.

The construction thus far described provides a reel frame having at one end two spaced plates 25 and 32, one fixed with respect to the other, the

outer (cap) plate being removable from the spacer posts and the latter being removable from the pillars, whenever disassembly is to be performed. A peripheral shoulder 35 may be formed around the cap plate and screw threads around the periphery of the head plate so that a cap ring 36 having a flange 37 may be fitted around both plates, the flange being adapted to seat itself against the shoulder 35. Screw threads 38 are formed interiorly of the cap ring for engagement with the peripheral threads of the head plate, whereby to cause the cap ring, when rotated, to advance axially with pressure against the cap plate where it normally remains during use of the reel. The protection thus afforded by the cap ring to the operating parts enclosed thereby is a feature that is more fully dealt with in my Patent No. 2,391,935 of January 1, 1946.

The cap plate in conjunction with the tail plate supports opposite bearings 40 and 41 for the spindle 42 of a spool 43, having opposite end flanges 44 of circular contour. These bearings are of any conventional type, so need not be described in detail.

Formed through the annular head plate 25, and slightly misaligned with respect to its axis, is the large circular opening 45 which gives it the characteristics of a ring. Within this annular ring may be accommodated a closure plate 46 having, if desired, a peripheral shoulder 47 which lies opposite the outturned periphery of the proximate spool flange 44. The closure plate is carried fixedly by the cap plate 32, as through the medium of three or more screws whose heads 48 overlie the outer face of the cap plate; the shanks 49 of these screws passing through the cap plate to engage fixedly with the closure plate which is maintained a fixed distance away from the cap plate by spacer sleeves 50 which surround the screw shanks.

In this construction the closure plate, although closely fitting into and substantially covering the head plate opening, is carried by the cap plate 32 through the medium of the three-point support just noted. The cap plate provides a mounting for a suitable train of gearing *g* which transmits motion from an operating handle 51 to the spool spindle 43 in the usual manner. If desired, the closure plate may also serve as an anchorage for one or more studs or bearings included in the gearing. The details of the bearings and gear train may be varied or modified along conventional lines. The cap and closure parts, together with the operating parts carried by one or both of them, constitute, in effect, a single unit which, when secured to the reel frame, is in driving relation with the reel therein. This relationship is maintained by certain locking means shortly to be explained in detail, but may be readily broken, whenever occasion requires, whereby to afford exposure of and access to the operating parts of the reel.

I have provided a novel and improved means for locking to the reel framework the cap plate assembly, i. e. the cap and closure plates together with the parts mounted thereon. This locking means, as shown in Fig. 6, may comprise a pair of knurled crescent disks 55 each extending through the major part of a circle to join with opposite ends of a concave face 56 whose curvature is substantially coincident with the periphery of the closure plate. Two such disks are desirably employed, arranged on opposite sides of the reel axis. Each disk is rotatably affixed to the head

plate 25 as by means of a threaded stud 57 which is entered into an axial opening therein. This stud may be provided with an enlarged cylindrical body 58 whereon the disk 55 is rotatably supported, and with a slotted head 59 in engagement with the outer face of the disk. The length of the stud body 58 is such as to provide a spacer which will assure to opposite faces of the disk freedom from pressure contact from the stud head 59 and from the head plate 25.

Each disk which lies to the inside of the cap ring 36 is so located that its arcuate face 56 may just clear the periphery of the closure plate 46 when the disk is rotated to the position that is indicated near the top of Fig. 6. When both disks are so adjusted, the cap plate assembly is free for axial movement so as to be removable from the reel framework. The normal locking position is indicated by the disk 55 which is shown near the bottom of Fig. 6. Here its convex peripheral portion is extended in part over the closure plate 46 so as to engage therewith. Separation of the cap plate assembly when both disks are in their locking position is, therefore, effectively prevented. The two disks are accessible for manipulation whenever the cap ring 36 is removed. No tools are required in this operation.

It is important that each disk, when adjusted to locking position, normally remain so. To accomplish this I provide in each disk a socket 61 extending into its body from its inner face; this socket accommodating a compression spring 62 which is normally projected toward the head plate 25 for engagement therewith. The friction thus provided by this spring engaging the head plate is sufficient to hold the disk in whatever rotative position it may then occupy except when an overpowering force is applied to rotate it to a different position.

I have also provided means whereby to limit the movements of each disk between its locking and unlocking positions. For this purpose the disk may be formed with an arcuate slot 65, opening upon the inner face of the disk, to receive a pin 66 which is anchored in the head plate 25 to project outwardly therefrom. This pin acts to limit rotation of the disk between the two positions shown in Fig. 6, in one of which the disk periphery is clear of the closure plate and in the other of which it is engaged therewith. It is manifest that manipulation by the finger or a small tool will serve to rotate each locking disk to its fully locked position, or vice versa, and that when either of these positions has been reached the user will be definitely apprised of that fact.

The particular means for locking the cap plate assembly to the reel may be variously modified, as indicated in Figs. 9-17 inclusive. Three suggestive forms of locking devices are shown and will now be described. It is to be understood that any of these forms may be employed with a reel of the general type which has been shown and described in connection with Figs. 1-6.

According to Figs. 9-11, I may employ a pair of generally triangular rocker plates 75 each having in its body a hole 76 through which may be entered the cylindrical body 77 of a threaded stud 78 which is anchored to the head plate 25. The stud body carries a head 79 in spaced relation to the rocker plate 75 and therebetween a coiled spring 80 which exerts opposing thrusts on the plate and stud head. Each rocker plate is formed with a nose 81 extending inwardly, also with a pair of spaced ears 82 and 83 which upstand from its base or outer edge to lie adjacent the inner face

of the cap ring 36. When this ring is applied in place, as shown in Figs. 9 and 10, there will be substantial engagement of both these ears with the cap ring, thus preventing any swinging movement of the rocker plate from its locking position. By some such means as this, the rocker plate is normally maintained in overlying relation to the closure plate of the head plate assembly. So long as either (or both) rocker plate remains in locking position the cap plate assembly is held securely locked to the reel frame. By removal of the cap ring, however, each rocker plate may be shifted to a different rotative position wherein its nose 81 is free of the closure plate; when this is done, the cap plate assembly may be detached as a unit. It is preferred that two such rocker plates be employed, each to be located at a point substantially opposite the other relative to the axis of the reel.

According to the showing of Figs. 12-14, two locking pins are arranged at substantially opposite sides of the reel, each pin having a cylindrical body 85 which is journaled for rotation within an opening through the cap plate 32. At the outer end of the pin is a knurled head 86 having a shoulder 87 adjacent its inner face. This shoulder is adapted to abut the outer face of the cap plate 32 so as to maintain the knurled head in spaced relation thereto. The inner end of the cylindrical body 85 may be reduced in diameter to provide a stud 88 which is threaded for engagement within a similarly formed opening in the head plate 25. When the locking pin is rotated to advance its threaded stud into operative engagement with the head plate, an axial pressure will be exerted upon the outer face of the cap plate 32 so as to lock the one to the other. Axial movement of the cap plate is arrested when it is seated on the shoulders at the bases of the necks 31 of the several spacer posts 29. Extending around the pin body 85 is a groove 89 wherein is fitted a split spring ring 89a whose outside diameter is sufficiently great to serve as a stop whereby to prevent axial movement of the locking pin outwardly through the cap plate. This stop ring is spaced from the shoulder 87 a distance sufficient to permit of limited axial movement of the locking pin whereby it may be manipulated into engaging relation with the coacting opening in the head plate. By this arrangement the two locking pins as per the construction of Figs. 12-14, are permanently assembled with the cap plate so as to be available always for facile engagement with the head plate whenever the cap plate assembly is to be secured to or detached from the reel frame.

In Figs. 15-17 I have suggested still another form of locking means that may be employed to secure the cap plate assembly to the reel frame. As shown, this comprises a plurality of axially socketed studs 90 anchored to the head plate 25, each projecting therefrom toward the cap plate 32 to serve as a spacer therefor. The open socketed end of each stud faces toward the cap plate to receive therein a post 91 which is anchored fixedly to the cap plate. When the cap plate assembly is secured to the reel frame, the posts and studs will be interfitting, as shown best in Fig. 16. To prevent normal separation of each post from its cooperating stud I may employ a wire spring having at one end a free arm 92 which is adapted to lie within an arcuate slot 93 formed through the wall of the stud. The spring is formed with a coil 94 which surrounds an anchoring pin 95 whereby the spring is carried by the head plate 25.

Desirably two of these locking devices are employed, arranged at points about opposite each other relative to the axis of the reel. The spring arm 92 in each case normally remains fitted within the stud slot 93 in a position to be engaged by the post 91 when entered therewithin. This post is provided with a circumferential groove 96 which is disposed at a point opposite the slot 93 when the post has been fully entered within the socket. The free end of the wire spring then engages the post groove to serve as a detent whereby to prevent normal axial movement of the post outwardly from the socketed stud. In some such way as this, the locking devices of Figs. 15-17 operate to hold the cap plate assembly in a fixed position relative to the reel frame. The cap ring 36, when screwed home to its final position, supplements this locking action.

It is a feature of this invention that I have provided a simple, yet readily manipulatable, means requiring no tool for its operation, whereby to free the cap plate assembly for removal from the reel framework. By the same token, the cap plate assembly may be readily locked to the reel framework when applied thereto. The operating parts for the reel remain fully protected within the enclosed space between the head and cap plates, yet are readily exposed to view, or made accessible for attention, whenever the cap plate assembly is removed from the reel. Any operation of adjustment, lubrication, or cleaning of the reel mechanism must oftentimes be performed when there is no tool available or opportunity to use shop facilities, consequently the arrangement herein disclosed is advantageous because it permits facile attention to the reel mechanism whenever and wherever the occasion may require. The important factor of a secure lock whereby the cap plate assembly is maintained securely in operative position upon the reel frame, is adequately met by the simple yet effective means provided for locking the one to the other. Once secured in operative position, there need be no concern about the cap plate assembly remaining so. Particularly is this true in the case of the rocker plate lock which is positively held in its locking position so long as the cap ring remains applied in place.

I claim:

1. In a fishing reel of the type which includes an annular head plate and as a separate unit a cap plate assembly having a closure plate adapted to be fitted within the confines of the opening in the head plate: means for locking the closure plate to the head plate comprising a crescent disk pivotally mounted on the head plate and movable from one position in which the concave face of the disk is clear of the closure plate to a second position in which one of the tips of the crescent disk is engaged with the closure plate to secure the same fixedly in its fitted position upon the head plate.
2. In a fishing reel of the type which includes an annular head plate and as a separate unit a cap plate assembly having a closure plate adapted to be fitted within the confines of the opening in the head plate: means for locking the closure plate to the head plate comprising a crescent disk pivotally mounted on the head plate and movable from one position in which the concave face of the disk is clear of the closure plate to a second position in which one of the tips of the crescent disk is engaged with the closure plate to secure the same fixedly in its fitted position upon the head plate, and spring

friction means interposed between the disk and head plate for resisting movement of the disk in either direction.

3. In a fishing reel of the type which includes an annular head plate and as a separate unit a cap plate assembly having a closure plate adapted to be fitted in a predetermined position within the opening of the head plate together with a cap ring in screw threaded engagement with the head plate and in abutting engagement with the cap plate adapted when rotatively advanced to maintain the closure plate in a predetermined position within the head plate opening, and means independent of the cap ring for locking the cap plate assembly to the head plate comprising an element carried by the head plate and mounted for movement thereon between two positions in one of which it advances to engage with the closure plate to maintain the same fixedly in fitted relation with the head plate and in the other of which it recedes to disengage from the closure plate to free the same together with the remaining parts of the cap plate assembly for axial movement away from the head plate.

4. In a fishing reel of the type which includes an annular head plate and as a separate unit a cap plate assembly having a closure plate adapted to be fitted in a predetermined position within the opening of the head plate together with a cap ring in screw threaded engagement with the head plate and in abutting engagement with the cap plate adapted when rotatively advanced to maintain the closure plate in a predetermined position within the head plate opening, means independent of the cap ring for locking the cap plate assembly to the head plate comprising an element carried by the head plate and mounted for movement thereon between two positions in one of which it advances to engage with the closure plate to maintain the same fixedly in fitted relation with the head plate and in the other of which it recedes to disengage from the closure plate to free the same together with the remaining parts of the cap plate assembly for axial movement away from the head plate, and means forming part of the locking element arranged to lie adjacent the inner face of the cap ring when the locking element is moved into engagement with the closure plate to prevent recession of the locking element to disengaging position relative thereto.

5. In a fishing reel of the type which includes an annular head plate and as a separate unit a cap plate assembly having a closure plate adapted to be fitted in a predetermined position within the opening of the head plate together with a cap ring in screw threaded engagement with the head plate and in abutting engagement with the cap plate adapted when rotatively advanced to maintain the closure plate in a predetermined position within the head plate opening, means independent of the cap ring for locking the cap plate assembly to the head plate comprising an element carried by the head plate and mounted for movement thereon between two positions in one of which it advances to engage with the closure plate to maintain the same fixedly in fitted relation with the head plate and in the other of which it recedes to disengage from the closure plate to free the same together with the remaining parts of the cap plate assembly for axial movement away from the head plate, limit stops for arresting movement of the locking element when in either of its two specified positions, and spring friction means interposed be-

tween the locking element and head plate for resisting movement of the locking element away from either position.

6. In a fishing reel of the type which includes an annular head plate and as a separate unit a cap plate assembly having a closure plate adapted to be fitted in a predetermined position within the opening of the head plate together with a cap ring in screw threaded engagement with the head plate and in abutting engagement with the cap plate adapted when rotatively advanced to maintain the closure plate in a predetermined position within the head plate opening, means independent of the cap ring for locking the cap plate assembly to the head plate comprising an element carried by the head plate and mounted for movement thereon between two positions in one of which it advances to engage with the closure plate to maintain the same fixedly in fitted relation with the head plate and in the other of which it recedes to disengage from the closure plate to free the same together with the remaining parts of the cap plate assembly for axial movement away from the head plate, means forming part of the locking element arranged to lie adjacent the inner face of the cap ring when the locking element is moved into engagement with the closure plate to prevent recession of the locking element to disengaging position relative thereto, and spring friction means in engagement with the locking element for resisting movement thereof from a selected position of adjustment.

7. In a fishing reel of the type which includes an annular head plate and as a separate unit a cap plate assembly having a closure plate adapted to be fitted in a predetermined position within the opening of the head plate together with a cap ring in screw threaded engagement with the head plate and in abutting engagement with the cap plate adapted when rotatively advanced to maintain the closure plate in a predetermined position within the head plate opening, means independent of the cap ring for locking the cap plate assembly to the head plate comprising an element pivotally carried by the head plate and mounted for swinging movement thereon between two positions in one of which it advances to engage with the closure plate to maintain the same fixedly in fitted relation with the head plate and in the other of which it recedes to disengage from the closure plate to free the same together with the remaining parts of the cap plate assembly for axial movement away from the head plate, and means on the locking element remote from the inwardly extending means adapted to lie adjacent the inner face of the cap ring, when the locking element is moved into position for engagement with the closure plate, to prevent disengagement of the inwardly extending means of the locking element from the closure plate.

WALTER WILLMAN.
